Inventor:

Heinrich Lux.

UNITED STATES PATENT OFFICE.

HEINRICH LUX, OF BERLIN, GERMANY.

PHOTOMETER.

Application filed May 1, 1924. Serial No. 710,441.

To all whom it may concern:

Be it known that I, HEINRICH LUX, a citizen of Germany, and a resident of Berlin, Germany, have invented new and useful

5 Improvements in Photometers, of which the following is a specification.

The present invention relates to photometers and has for its object to provide a photometer by means of which the brightness (luminous density) of surfaces which radiate light or reflect light, can be directly ascertained without the necessity of comparing said surface with a light-source of known candle power. Owing to this fact 10 I have been able to provide a photometer which can be readily applied for measuring quickly and sufficiently accurate the illumination, for instance, of working places, dwelling rooms, cellars, storing 15 rooms, etc., as well as the candle power of light sources, such for instance, as the head lights of power cars, and the like. My invention is based on the well-known interference phenomenon obtained by superposing 20 two transparent plates having parallel lines ruled thereon, and turning said plates so that said ruled lines cross each other. According to the angle under which the 25 parallel lines intersect one another, the crossing points form lines or bands of smaller or thicker widths. The smaller the angle is, the thicker appear these secondary lines, and vice versa. Now, if the surface 30 the brightness of which is to be measured, is relatively dark, the lined plates need only to be turned slightly to render those secondary bands or lines as invisible to a normal eye. It is known that visual signs, such, for 35 instance, as fine lines, small printed letters, and the like, can be perceived the more distinctly, the better they are illuminated or the stronger their brightness is. In the 40 case of the brightness being comparatively slight, the visual signs must be thicker or 45 larger than if the brightness is comparatively strong. Reversely, that slighter or stronger fineness of the visual signs which can just be perceived can be used as a measure for ascertaining the existing brightness or illumination. Now, if one or the 50 other of the two plates having parallel lines ruled is turned, there then arise if the angle of turning is small a few and strong secondary lines; if the turning is 55 continued, the secondary lines become finer and finer and can, finally, be perceived as

visual signs only if the strength of the brightness or illumination is increased correspondingly. If a distinct brightness or illumination exists which is to be judged of, one of the ruled plates must be turned until the secondary lines which become finer and finer can no more be perceived. Thus, the angle of crossing of the ruled lines of two transparent plates forms the photometric criterion for my new photometer which I will now describe with reference to the drawings forming a part of this application, and illustrating by way of example an embodiment of my invention.

70 Fig. 1 is a vertical section, and

Fig. 2 a side view of the object-end of the photometer.

Figs. 3 and 4 show plates having parallel 75 lines ruled thereon.

Fig. 5 illustrates the interference phenomenon obtained by superposing said plates so that the ruled lines thereon cross each other.

Figs. 6 and 7 illustrate, in a plan and 80 side view, respectively, a goniometer device applied to the object-end of the photometer shown in Figures 1 and 2.

The photometer illustrated comprises two telescopically arranged tubes t t^1 of which 85 t^1 is provided with an end wall p having a contracted sight hole corresponding with another sight hole provided in a diaphragm B arranged at a distance from said end wall p . The tube t^1 can be telescopically moved 90 within the tube t in order to adjust the instrument to that range of vision at which the secondary lines can be clearly distinguished. To the tube t is affixed an annular member b having a circumferential groove 95 n . In a central aperture b^1 of this member is mounted a plate r^2 in such a manner that its outer surface lies flush with the outer surface of the annular member b . Another plate r^1 is mounted in another annular 100 member a revolvably attached to the member b , and coupled therewith by pins n^1 engaging the groove n . Both plates r^1 and r^2 are provided with ruled lines as shown in Figures 3 and 4.

105 The relative angular position of the plates r^1 and r^2 can be varied by turning the movable member a on the stationary member b , and the adjustment thus effected can be ascertained from a graduation i (Fig. 2) 110 provided on the member a and co-operating with a mark i' of the member b . Figure 5

2
illustrates roughly the appearance of the secondary lines β , when the superposed plates r^1 , r^2 have been turned relatively to one another.

5 Since within those degrees of brightness which come into regard with respect to good seeing, and which lie between 10 Millilambert to 1 Lambert, the visual acuity of all 10 normal eyes shows only very slight differences, the latter may be neglected, without thereby perceptibly affecting the accuracy of my new photometer for all practical purposes.

I gauge the graduation scale i by means 15 of a plurality of surfaces the light emitting power of which is accurately known.

A finer graduation can be obtained by enlarging the arc of the scale, as for instance, by means of frame legs s and s^1 20 which are secured to the annular member a by means of an angle piece h . The latter is provided with a pin g on which is revolvably mounted a pinion f engaging a curved rack e secured to the annular member a . To the pinion f is fixedly secured 25 a pointer z co-operating with a scale i^2 . Any angular turn between the members a and b is indicated considerably enlarged on the scale i^2 by the pointer z .

30 I am aware that any other goniometer device may be used in combination with my new photometer, so I do not limit my claim to any constructive particulars illustrated in the drawings. The mode of using my new photometer is as follows. Before I 35 view the surface or lamp the candle power of which I desire to determine, I adjust the tubular length of the apparatus to the visual acuity of my eye by constructing or extending the telescopic tubes t and t^1 until I clearly distinguish the lines ruled on plate r^2 which lines cover the corresponding lines on plate r^1 when the scale i (in Fig. 2), or i^2 40 (in Fig. 6) indicates a small difference from the zero position. Having thus adjusted the photometer I view through it the surface or light source to be measured and slowly turn the members a and b relatively to each other until the secondary lines or 45 bands appearing on said plates r^2 , r^1 grow faint and finally become invisible within the light viewed. The candle power of this light may then be ascertained from the position of the mark i^1 (in Fig. 2) or the pointer z (in Figure 6). As a matter of fact I may 50 follow the opposite course in gauging the scale by fixing the zero position at that angular relative position of the plates r^1 55

and r^2 wherein the secondary lines are invisible and then vary this angle until said 60 secondary lines become clearly distinguishable.

What I claim and desire to secure by Letters Patent of the United States is:—

1. A photometer, comprising, in combination, a pair of superposed transparent plates each having parallel lines ruled thereon, means for turning said plates relatively to each other, a scale indicating the variable relative angular position between said 70 plates, said scale being gauged so that each scale mark indicates a tested brightness.

2. A photometer, comprising, in combination, a pair of superposed transparent plates having parallel lines ruled thereon, means for turning said plates relatively to each other, a scale indicating the variable relative angular positions between said plates, said scale being gauged so that each scale mark indicates a tested brightness, and a 75 hollow structure axially extending the space in front of one of said plates and adapted to assist the human eye in examining any variation in the thickness of the secondary lines appearing when said respective lines 80 on said plates cross each other.

3. A photometer, comprising, in combination, a pair of superposed transparent plates each having parallel lines ruled thereon, means for turning said plates relatively to each other, a graduated member adapted to indicate the variable angular relative positions between said plates, said scale being gauged so that each scale mark indicates a tested brightness, and a goniometer device 90 95 combined with said plates and adapted to render any variation in the relative angular position between said plates perceptible.

4. A photometer, comprising, in combination, a pair of superposed transparent plates 100 each having parallel lines ruled thereon, means for turning said plates relatively to each other, a scale indicating the variable angular relative positions between said plates, said scale being gauged so that each 105 scale mark indicates a tested brightness, a hollow structure axially extending the space in front of one of said plates and adapted to assist the human eye in examining any variation in the thickness of the secondary 110 lines appearing when said lines on said plates cross each other, and a goniometer device adapted to render a variation in the angular relative positions between said plates perceptible.

DR. HEINRICH LUX.
